UNITED STATES PATENT OFFICE.

D ANGELO BARBIERI, OF MILAN, ITALY.

COMBINED ELECTRIC PIANOFORTE AND ORGAN.

Application filed January 4, 1923, Serial No. 310,681, and in Italy January 4, 1922.

This invention has for its object to provide an improved electric musical instrument comprising a pianoforte of any type, upright or grand, and an organ. These two instruments may be located close together or apart, being connected to each other through the medium of a plurality of electrical devices operated either by the keyboard of the pianoforte proper or by an auxiliary keyboard mounted on the pianoforte from which it can be removed, being designed exclusively for the organ or by means of the pedal mechanism which can likewise be mounted and dismounted readily.

The accompanying drawings illustrate by way of example one embodiment of this invention, illustrating the improved musical electric instrument, that is to say, a pianoforte and an organ connected electrically together in any suitable manner. In these drawings:—

Figures 1 and 1^a taken together are a vertical section of an ordinary pianoforte connected electrically to an organ by means of an improved mechanism forming the subject matter of the present invention.

Figure 2 is a separate view of the details of an electric mechanism actuated by the keyboard of the pianoforte.

Figure 3 is a view of the details of an electric interrupting mechanism with movable contacts designed for transmitting the movement of the pianoforte keys to determined parts of the organ, or for opening the circuits relating thereto, according to the construction which it is preferred to give to the said movable contacts.

Figure 4 is a diagrammatic view of the coupling of the coils designed for opening the valves for admitting air into the organ pipes in the case where the said coils have a normal construction; the said coils being provided with a single winding.

Figure 5 is a diagrammatic view of the coupling of the coils designed for opening the valves for the admission of air into the organ pipes in the case where these coils are provided with two windings of which the first winding is connected to a keyboard, and the second winding is connected to the other keyboard of the instrument.

Figure 6 is a vertical section of the apparatus comprising the electric contacts aforesaid and designed, for instance, for

playing an organ at a distance by means of the keyboard of a pianoforte.

Figure 7 is a plan of the various parts of the apparatus shown in Figure 6, the general arrangement of which is separated from the other portions.

Figure 8 is a front view of the said apparatus mounted on the keyboard.

Figure 9 shows the different combinations which can be made by moving the special eccentrics or cams with which the said apparatus is provided. The said combinations are shown in the positions that are most suitable for the proper working of the organ.

Figure 10 shows the same cams adapted by means of devices to correspond with the combination shown in Figure 9.

Figures 11 and 12 are diagrammatic views of different arrangements of the double coil forming part of the invention.

In the various figures the same numbers are employed to designate the same parts.

Referring first to Figures 1-4; 1 is the pianoforte provided with a keyboard 2 (hereinafter referred to as the keyboard proper) and a second keyboard 3 corresponding to the mechanism of the organ 39. This keyboard may be mounted or dismounted with the greatest facility. 4 is the keyboard corresponding to the bass notes of the pianoforte: it is mounted likewise on the pianoforte in such a manner as to be readily dismounted therefrom. 5 is an apparatus comprising a plurality of contacts 90 designed to be actuated by the keyboard 2. For each key of the latter there is provided a small spring 6 for closing an electric circuit acting upon the organ when the corresponding key of the keyboard 2 is depressed. 7 is a stem with which each key of the keyboard 2 is provided and which according to the movement of the said key allows of raising or depressing the corresponding spring 6. 8 is a contact for closing the circuit of the spring 6. 9 and 10 are two stops forming part of the apparatus 5; they are designed, each in its turn, to close the electric circuit of one half and the electric circuit of the other half of a solenoid coil 105 for coupling the pianoforte 1 with the organ or for detaching a determined portion of said organ 39 therefrom according to the portion of the latter into which the respective current is sent. This current may also

70

110

be an alternating current in view of the fact that the number of stops analogous to those 9 and 10, and consequently the number of double coils 11 corresponds to the number of 5 registers of the organ which can be brought into operation by the pianoforte; 12 and 13 are groups of movable contacts controlled by the corresponding double coil 11; they are designed to transmit the current to the 10 coils of the various registers. 14 is a dividing contact for transmitting current to the springs 15 and 16 of the movable groups 12 and 13. 17 and 18 are springs taking current from the movable groups 12 and 13 for 15 transmission to the coils of the respective registers. 19 is a coil designed to cause only one register to sound; 20 are coils for playing two registers. 21 are valves for discharging the air from the chambers of the 20 organ. 22 are the air passages. 23 are the pipes of the various registers; 24 is the air duct for operating the organ pipes. 25 is the air inlet duct of the bellows 26 operated by the motor 27 for the reservoir 28. 29 is 25 an apparatus comprising multiple contacts similar to the apparatus 5, but in connection with the keyboard 3 of the apparatus 29, which is provided with contact springs 30 for the stems 31 fixed to the keys of the 30 keyboard 3 for operating the small springs 30 of the fixed contacts 32 and of the stops 33, 34, which are similar to those marked 9 and 10.

35 are pedals for operating the registers of the organ mechanism 4. 36 is a lever, by 35 means of which the corresponding coil 11 can depress the corresponding group of contacts 12 and 13. 37 and 38 are leads for transmitting the electric current from the devices 19 and 20, contacts 5 and 29, and 40 keyboards 2 and 3 to the coils of the organ 39 through the respective groups of the movable contacts 12 and 13. 40 is an apparatus comprising contacts of the pedal keyboard 4, analogous to the devices 5 and 29. 41 is 45 a lead for transmitting electric current from the apparatus 40, said current passing also through the groups of movable contacts at the coils of the double basses of the organ. The operation of the improved musical instrument is produced by the passage of the 50 electric current which can be an alternating current and which is caused to flow in the circuits of the solenoid coils when the circuits are closed by means of the keys of the keyboards and the pedals; these circuits include the groups of movable contacts and the coils for actuating the air valves in the 55 chambers of the organ.

From the foregoing the operation of the 60 improved instrument will be readily understood.

When it is desired to play one or more voices of the organ conjointly with the pianoforte, the player, after having started the 65 motor 27 for driving the organ bellows 26

pushes the stop or stops 9 corresponding to the required voices and which, by closing the circuit of one half of the relative solenoid coil 11, thereby moves the core of the said solenoid so as to depress by means of the corresponding lever 36 the group of contacts 12 or 13 or the two groups together according to the case. In this manner on the depression of any key of the keyboard 2 there will be closed through the corresponding spring 6 the electric circuit of the coil 19 or of the coils 20 or of all these coils together according to the groups of depressed contacts, thereby producing the rise of the cores of the said coils and consequently the opening of the corresponding valve 21 which will bring the corresponding pipes 23 into play.

If on the contrary by pushing the stops 10 in such a manner that the circuit of the second part of the double solenoid coils 11 is closed and the core is moved, there will be produced a rise of the groups of movable contacts 12 and 13 whereby the circuits of the coils 19, 20 will be opened, even if the keys of the keyboard 2 are pressed, so that the pianoforte will sound alone without bringing the organ in any way into play.

If it then be desired to play with one hand the pianoforte alone or the pianoforte conjointly with a voice of the organ and to play with the other hand one or more instruments comprised in the portion of the organ which is dependent upon the keyboard 36, it is possible to do so by performing a manoeuvre similar to that already described with reference to the keyboard 2 of the piano. As a matter of fact the keyboard 3 comprises likewise, as already stated, an arrangement of contacts 29 with its operating stops 33, 34 having its own lead 38 with its group of movable contacts similar to those 12, 13, and its operating coil similar to the coil 11.

The coils 19 and 20 take their current either from the lead of the keyboard 2 or from the lead of the keyboard 3, and may be actuated at will either from one or the other keyboard. The same arrangement applies also to the pedal keyboard 4 which has its own contact apparatus 40 and its operating stop is in the form of a small pedal 35. It is advisable to note that the solenoid coil for operating the corresponding group of movable contacts, as well as the solenoid for operating the valves for bringing the organ pipes into play, can be operated also by means of alternating current.

In order to be able, if necessary, to play with a keyboard, in unison a plurality of registers, for instance a flute and a viola, and by means of another keyboard a single register, for instance, the flute alone, which is not possible to do by using a solenoid composed of only one coil as above described and

shown, recourse may be had to a solenoid with a double coil as shown in Figure 5 in which case one wire of the solenoid is connected to one of the keyboards and the other wire is connected to the other keyboard. In this manner there is obtained for each keyboard an independent movement, just as if each keyboard has its own solenoid.

Referring to Figures 4 and 5—2 and 3 are the two keyboards of the instrument; 19, 19' is the solenoid for playing the flutes; 19'', 19''' are the solenoids for playing the violas; 42, 43 are the switches which connect respectively the solenoids 19 and 19' with the solenoids 19'' and 19'''.

In the case of Figure 4, each of the solenoids 19, 19', 19'', and 19''' is provided with a single coil indicated in the drawings by the numerals 44, 44', 44'', 44''' respectively, which coil, in receiving its current either from the keyboard 2 or from the keyboard 3, brings into operation the corresponding core of the respective solenoid; the cores of the several solenoids being indicated by 45, 25 45', 45'', 45'''.

In the case illustrated in Figure 5, on the contrary these solenoids 19, 19', 19'', 19''' are provided with coils 44, 44', 44'', 44''' and coils 46, 46', 46'', 46''' ; the first of 30 these two sets of coils being connected to the keyboard 2, whereas the other set is connected to the keyboard 3.

Referring to Figures 6 and 10, the multiple electric contact apparatus comprises a box 66 consisting of a body U-shaped of iron or brass the length of which exceeds that of the keyboard by so much as is necessary to enable it to rest with its ends upon the supports 67. This box is closed at the 40 top by a plate 68. In this box, which is arranged on the rear part of the keyboard in order to avoid interfering with the movement of the fingers of the player, are lodged insulating blocks 69 and 70 on the former 45 of which (69) there are mounted the fixed contacts 71 of the end 72 from which leads one of the wires of the corresponding circuits of the receiving instrument or machine. On the second insulating block 70 by means 50 of screws 73 constituting the terminals for clamping the other wire of the same circuit there are fixed a plurality of small springs 74 equal in number to the keys. These 55 springs are fixed to the stems 75 sliding in the interior of the block 69 and resting upon the keys of the keyboard. The depressing of each white key 76 or black key 77 thus causes the corresponding stem 75 to descend and carry with it the corresponding spring 71, 60 thereby closing the corresponding circuit.

When the said multiple electric contact apparatus is to be employed for playing the organ at a distance as in the example illustrated in the drawings, the said apparatus 65 may be constructed with advantage in a

slightly more complicated manner as hereinafter described.

The stem 75, instead of carrying only one spring 74, carries at its upper end two such springs (Fig. 7) with the corresponding contact points 78 and 79. Below each spring there is an eccentric 90 which is mounted like all the other similar eccentrics of the other springs on a common shaft 91 operated by a special sector 92 comprising 75 helical cams. This sector is set in motion by means of three co-axial solenoids 93 (Fig. 8). These solenoids are adapted to move the shaft 91 and consequently the eccentrics 90 on the said shaft, into three different positions. The eccentrics of the two springs of each stem are fixed in positions 180° apart.

By means of this apparatus there can be sounded, for instance, through the medium 85 of the springs 74, the corresponding note upon the organ, and by means of the spring 74' the octave of that note, which will be readily understood in the light of the following remarks.

Assuming for instance, that the eccentrics 90 have been moved into the position *a*, in Figure 10, which is here designated the normal position, then on playing one of the keys 94, 95, 96 (Fig. 9), only the corresponding spring 74' will be supported by the eccentric 90, and consequently, the pipe 94 or 95 or 96 will sound according to the circumstances of the case.

When the eccentrics 90 are moved into the 100 position *b* of Figure 10, say by the hand of another person, then on the depressing of each key, two springs will be depressed and by this means the sound of two notes will be obtained for each key so that on playing the key 94 its octave 95 will also be played and by depressing the key 95 the pipes 96 and 97 will be played.

Finally, on moving the eccentrics into the 110 position *c* Fig. 10, for instance, the octave, this will prevent the springs 75 from being depressed on to the keys and only the springs 74 will be depressed. Consequently the operation of the key 94 will play only one pipe 115 95. The operation of the key 95 will play only its octave 96, and the operation of the key 96 will play only the pipe 97.

Every organist will readily appreciate the advantages and the varied effects which this 120 very simple system of contacts can produce.

The accompanying drawings show readily the diversity of operations which can be performed with the two systems illustrated therein.

What I claim is:—

1. In combination a piano including a keyboard, an organ, an auxiliary keyboard only serving for playing the organ, a pedal counterbase keyboard applied to the piano, electric solenoids for actuating the air valves of 130

the pipes of the organ, electric circuits connecting the keys of the different keyboards to said solenoids, contact devices inserted in said circuits and apt to be acted by the keys 5 of the keyboards, movable contacts interposed in said circuits, means connecting said movable contacts in groups and double solenoids acting said groups of movable contacts in such a manner as either to allow or 10 to prevent the contact devices actuated by the keys of the keyboards closing the corresponding electric circuits.

2. An apparatus as claimed in claim 1, characterized in that each of the double solenoids acting the groups of movable contacts is so constituted that, according as current is passed by the actuation of corresponding stops into one or the other part of said solenoids, its core unit is moved in one or the 20 other direction to raise or depress, by means of a suitable lever, the corresponding group of movable contact.

3. An apparatus as claimed in claim 1 characterized in that each of the said contact devices includes a stationary contact or a spring contact member arranged to engage the stationary contact member, and a stem engaged with a key of one of the keyboards and adapted, when said key is in a position 30 of rest, to maintain the spring contact out of engagement with the stationary contact member.

4. An apparatus as claimed in claim 1 characterized in that the said movable contacts and the connecting means therefor including, the stationary contact member, mov-

able members arranged on opposite sides of and having permanent electrical connection with the stationary contact member, and a plurality of pairs of spring contact members, 40 the contact members of each pair being engaged with the movable contact members and the latter being adapted upon movement thereof to disengage the spring contact members. 45

5. An apparatus of the character described, a housing, an insulating member supported in said housing, a plurality of stems mounted in the insulating member and adapted to be arranged above the keys of a 50 keyboard, a second insulating member arranged in said housing, a plurality of spring contact members secured to the second insulating member, said spring contact members being engaged and operated by said stems and relatively stationary contact members being engaged by the spring contact members.

6. A combination with the keyboard of a musical instrument, a housing arranged 60 above the keyboard, a stem engageable and operable by each key of the keyboard, a pair of spring contact members adapted to be engaged and actuated by each stem, relatively stationary contacts adapted to be engaged 65 by the spring contact members, cams adapted to move and maintain the spring contact members in inoperative position, and electromagnetic means for actuating said cams.

In testimony whereof I affix my signature.

D ANGELO BARBIERI.
